UNITED STATES PATENT OFFICE.

FRANK E. LONAS, OF NEW YORK, N. Y.

LUBRICATING SYSTEM FOR INTERNAL-COMBUSTION ENGINES.

Application filed September 26, 1925. Serial No 58,770.

This invention relates to internal combustion engines and particularly to an improved system of lubrication for the several rotary and reciprocating parts of the engine; and 5 the object of the invention is to provide a system of lubrication contained entirely within the cylinder structure and the crank case thereof, the system being of the pressure feed type with pipes or passages formed integral 10 or mounted in connection with the cylinder structure for directing the oil from a pump or other pressure element to the several bearings and moving parts; a further object being to provide a settling chamber into and 15 through which the lubricating oil is first passed from the pressure element, said chamber being provided with means whereby a quantity of oil is stored therein to facilitate the quick feed of oil to the working parts in 20 the initial starting of the engine; a further object being to provide supplemental storage means for storing excess supply of lubricant with automatically actuated means for providing a replenishing feed to the oil in the 25 crank case and directly to the feed line of the supply to the working parts, whereby a substantially constant level of lubricating oil is maintained in the crank case; and further whereby the lubricating properties of the 30 oil may be maintained for an indefinite period of time; a further object being to provide large straining surfaces for straining the oil after it has been used for the lubrication of the parts, and prior to its reuse in 35 the operation of the engine; a still further object being to provide a lubricating system in which all or substantially all of the lubricating pipes or passages are exposed to the cooling water of the engine prior to the passage 40 of the oil to the working parts, whereby the oil may be supplied to the working parts at a temperature substantially equal to that of the temperature of the water, thus maintaining to a greater degree the lubricating 45 properties of the oil and facilitating the use of proper grades of oil for the working parts of the engine through all seasons and regardless of atmospheric temperatures; and with these and other objects in view, the invention 50 consists in a lubricating system of the class and for the purpose specified, which is simple

in construction and operation and efficient in use and which is constructed as herein-after described and claimed.

The invention is fully disclosed in the following specification, of which the accompanying drawing forms a part, in which the separate parts of my improvement are designated by suitable reference characters in each of the views, and in which:—

Fig. 1 is a side view of an engine with parts of the construction broken away and in section and showing my improved lubricating system.

Fig. 2 is a partial transverse section on the line 2—2 of Fig. 1 on an enlarged scale and with parts of the construction broken away.

Fig. 3 is a section on the line 3—3 of Fig. 1 on an enlarged scale with part of the construction broken away; and,

Fig. 4 is a transverse sectional view through the central part of the crank case portion of the engine, showing a modification.

For the purpose of illustrating one use of my improved lubricating system, I have shown in the accompanying drawings what is known as a sleeve valve engine, the specific structure of which is shown, described and claimed in a copending application, Serial No. 54,202, filed September 3, 1925. In the drawing, 5 represents the main cylinder structure having spaced outer and inner walls 6 and 7 with a water jacket 8 therebetween and with intake and exhaust manifolds 9 and 10 positioned within the water jacket 8 in spaced relation and as an integral part of the inner wall 7. The cylinder proper 11 is mounted within and in spaced relation to the wall 7 and the sleeve valve 12 reciprocates in the space between the wall 7 and the cylinder proper.

A cylinder cover 13 is mounted upon the main cylinder structure 5 and contains a water chamber 14 which is in communication with the jacket 8 and within the cover 13 and above the top of the main cylinder structure 5 is a chamber 15 within which is mounted on opposite sides of the cylinder structure, crank shafts 16 and 17 mounted in suitable bearings 18 and 19 which extend

above and are formed integral with the cylinder structure. The shafts 16 and 17 are adapted to operate the sleeve valve 12, or a number of such valves, through connecting means 20 in the manner of other engines of this class.

At 21, I have shown the crank case which is mounted in connection with the main cylinder structure 5 and at 22 is shown the usual crank shaft of the engine on the cranks of which the connecting rods 23 of the pistons 24 are mounted. It will be noted that the water jacket 8 extends downwardly around the crank case portion of the cylinder 5 as seen at 25 whereby the cooling water of the engine may be exposed to supplemental lubricating oil storage chambers 26 and 27 disposed at the opposite sides of the cylinder structure and formed integral therewith as 20 clearly seen in Fig. 2 of the drawing. The chambers 26 and 27 are separate and are each provided with filling apertures closed by plugs 28, one of which is seen in Fig. 2 of the drawing, the chambers being preferably provided with elongated screens 29 to strain the oil passed into said chambers, the other plugs 30 being provided to drain the chambers at will, one of said plugs being shown in Fig. 2 of the drawing. Float levels 31 may also be employed for the separate chambers, one of said levels being seen in Fig. 1 of the drawing.

In the construction shown, the engine employs two carbureters 32 one at each side of the engine, one of the carbureters being shown in Fig. 1 of the drawing and the other in Fig. 2 and coupled with the butterfly valve operating means of each carbureter is a link and lever construction 33 for actuating a needle valve 34 which passes through a plug 35 at the top of each chamber 26-27 and enters and is operable in a valve plug 36 at the bottom of each chamber, said plugs having passages 37 which open into said chambers 45 and communicate with passages 38 in the cylinder structure which open into the crank case 21, see Fig. 2 of the drawing. The taper on the needle valves 34 serves to control the feed, and means 39 in the form of a turn buckle is provided to adjust the needle valves to the suitable positions in order to maintain a pre-determined flow of lubricating oil under operating conditions.

The crank case 21 tapers downwardly to the center thereof as seen in Fig. 1 of the drawing and a large screening 40 is provided for straining the oil which drops into the crank case prior to its passage into a chamber 41 below the screen, said chamber opening into a feed chamber 42 formed within the crank case through ports 43 and a feed pipe 44 communicates with the chamber 42 through a strainer 45, note Fig. 1 of the drawing. The pipe 44 leads to a pump or other pressure element 46 for feeding the oil to the several working

parts of the engine under pressure, the pump 46 being driven from a gear or pinion 47 on the crank shaft of the engine, meshing with a gear 48 coupled with the pump shaft as seen at 49, Fig. 3 of the drawing; the gear 48 being mounted on a vertical shaft 50 which also operates the crank shafts 16 and 17 through a gear 51 on the shaft 50, and gears 52 and 53 on the shafts 16 and 17 respectively, and the fan shaft 54 is also driven through the shaft 50 by a gear 55 on the shaft 50 and a gear 56 on the fan shaft.

The gears 47 and 48 are mounted within a housing 57 positioned within the crank case and coupled with the cylinder structure and partially formed by said cylinder structure, and into which oil is passed directly from the pump through a nozzle 58 which communicates with the discharge pipe or passage 59 from the pump. The pipe 59 opens into an oil settling and feed chamber 60 formed in the main cylinder structure and independent of the chambers 26 and 27, the communication being formed by a pipe 61 which couples directly with the pipe or passage 59 and opens into the top of the chamber 60 whereby the oil from the pump passes first into the chamber 60 and from said chamber through the system. A drain plug 62 is provided at the bottom of the chamber 60 for draining the oil or sediment from said chamber at will.

The oil, after passing into the chamber 60 from the pump 46 in the operation of the engine, is directed through the system by first entering an extension 63 at the top of the chamber 60, see Fig. 1, and thus through a horizontal pipe 64 and a vertical pipe 65. The pipe 64 extends longitudinally of the engine and through the water jacket 8 at one side of the cylinder proper 11, note Fig. 2 of the drawing, and coupled with this pipe are a number of depending pipes 64^a which lead and open directly into all of the bearings 22^a of the crank shaft 22.

The vertical pipe 65 is connected at its upper end with a coupling 67 formed integral with the main cylinder structure 5, see Fig. 3 of the drawing, and communicating with this coupling is a pipe or pipes 68 which extend to the opposite sides of the engine and longitudinally thereof and are exposed to the water jacket 8, note Fig. 2 of the drawing. These pipes also pass through the bearing blocks 18 and 19 for the shafts 16 and 17, and the bearings for said shafts in said blocks are lubricated by holes 69 drilled through the bearing blocks and into the pipes 68. The pipes 68 as well as the pipes 64 and 65 may be cast integral with the cylinder structure or the cylinder fashioned to form passages therethrough, and in the event that a single pipe 68 is employed, the same will be of U-shaped or yoke-shaped form and will be parted at the coupling 67 by drilling a hole downwardly into said coupling and closing the same by a

plug 70, note Fig. 3 of the drawing. The oil fed to the front end bearing blocks 18 and 19 may also pass through ports 71 formed in said shafts and opening into annular grooves 5 or chambers 72 around the shafts 16 and 17 where the gears 52 and 53 are mounted thereon and out through radial apertures 73 formed in both of said gears to lubricate said gears as well as the gear 51. From the foregoing, it will be apparent that the oil from the pump 46 after it has passed into the chamber 60 and from this point to the point of supply direct to the parts to be lubricated, is exposed to the cooling water of the engine 10 in its passage through the pipes 64 and 65 as well as the pipes 68 and 64^a, thus maintaining the lubricating oil at a temperature substantially equal to that of the temperature of the cooling water. Further, the oil discharged from the bearings and through the working parts for return to the crank case, passes around the cooled cylinder walls through the passage 66 and a similar passage 66^a provided at the opposite end of the motor 15 or downwardly around the sleeve valves and through passages 74 which also open into the crank case structure indirectly, one of said passages being shown in Fig. 1 of the drawing, the oil passing into and around said 20 sleeve valves through ports 75 in the top cross-heads of said valves, the oil coming from the drip or surplus of the supply fed to the bearings for the shafts 16 and 17. The pistons and connecting rod bearings are supplied with lubrication in the splash by the overflow of the 25 main bearings as will be apparent.

I also preferably provide a communication between one of the passages 38 and the feed pipe 44 by means of a pipe 76 whereby 30 in addition to replenishing the oil supplied to the crank case 21 from the auxiliary or supplemental supply chambers 26-27, a direct supply of fresh oil may be passed from one of these chambers for example the chamber 26, directly into the feed pipe 44 whereby 35 by a small supply of fresh lubricating oil is constantly directed to all of the bearings or working parts, thus maintaining a high standard of lubricating properties to the oil 40 in all operating conditions.

It will be understood that the principle of my improved system resides in providing in the supplemental storage chambers 26 and 27, an excess supply of lubricating oil, and 45 the communication between the chambers 26 and 27 separately with the crank case 21 is normally shut off when the engine is not in operation, and after the engine has started 50 through the operation of the throttle or butterfly valve of the carburetors, the needle valves 34 are raised, permitting a small amount of the oil to drop by gravity into the crank case to maintain a substantially 55 fixed level of oil in the crank case by replenishing the consumed oil in the engine op-

eration or that part of the oil which is wasted, burned up or otherwise disposed of, and this replenishing of oil to maintain a fixed level or substantially fixed level, may be regulated by the adjustable means 39 to suit the conditions of the engine in all stages of operation. In addition to this supply, the supply direct to the feed pipe 44 will be excited or encouraged by the velocity of flow of oil through said pipe caused by the pump 70 action to suck or draw oil from one of the chambers 26-27 whereby a supply of fresh oil from the reserve storage is introduced directly into the oil drawn from the crank case. 75

With my improved system, I maintain that the lubricating properties or values of the oil may be kept at a substantially high degree for an indefinite period of time without changing the oil in the crank case, in that a constant supply of fresh oil is provided, not 80 only to the crank case but directly to the supply to the working parts, and further by reason of the fact that the lubricating oil is maintained at substantially an equal temperature to the temperature of the cooling water, 85 thus preserving and maintaining the lubricating properties of the oil and facilitating the use of an oil of the proper standard in all operating conditions of the engine. It will be understood that the oil is maintained 90 in the chambers 26 and 27 at substantially a fixed level by inserting the new oil into said chambers whenever replenishing is necessary. The crank case may be initially 95 filled through any suitable means in the usual manner, and the desired level of oil may be maintained in the crank case 21 by the provision of a pet-cock 77, note Fig. 1, or any other means.

It will be understood that the primary 100 function of the settling and feed chamber 60 is to provide a storage for the lubricating oil between the pump and the feed tubes or pipes whereby substantially instantaneous feed of oil to the working parts may be provided 105 when the engine is started. It will also be understood that the needle valves 34 which are actuated by the throttle or butterfly valve of the carburetors operate to increase the replenishing supply of oil to the crank case as 110 the speed of the motor is increased, it being apparent that this replenishing supply at any stage is but slight and is adjusted to compensate for the loss or consumption of 115 the lubricating oil.

In Fig. 4 of the drawing is shown a modified form of construction for automatically and positively maintaining a fixed level of oil in the crank case. In this form of construction, the strainer 45 and the pipe 44 are 120 positioned at one side of the crank case centrally thereof as well as the housing 42. Positioned at one side of the housing 42 is a supplemental housing 78 for a plunger float 125 79 movably mounted in said housing, and oil 130

is admitted into the housing 78 through an aperture 80 at the lower end thereof whereby the level of oil in the housing will be the same as in the crank case.

5 In the construction shown in Fig. 4, I connect with both of the discharge passages 38 leading from the auxiliary storage chambers 26 and 27 by way of the needle valves 34, pipes 81 and 82 which are coupled together as seen at 83 and are in communication with a coupling block or union 84 as seen at 85, the block 84 and pipes 81 and 82 being positioned beneath one of the bearings of the crank shaft in order not to interfere 10 in any way with the throw of the cranks. Coupled with the block 84 is a pipe 86 which is also in communication with the pipe 44, and another pipe 87 is coupled with the block 84 and extends downwardly into the oil within 15 the crank case 21 and below the normal level of oil therein. The float 79 is provided with a rod which extends upwardly through a plug 88 in the block 84 and is provided within the chamber of the block with a ball 20 valve 90 adapted to seat upon the plug 88 and also to form a seat and closure for the communication of the pipes 81 and 82 with the block 84 as at 85.

With the form of construction shown in 25 Fig. 4 of the drawing, it will be understood that when the engine is in operation, oil will drop by gravity from the auxiliary chambers 26 and 27 into the chamber within the block 84, and pass from said chamber into the pipe 44 and also into the crank case 21 when the level 30 of oil is at the desired point or when the oil is below the desired level and the feed of oil to the crank case will raise the level of oil to the desired point. In the event of a tendency to 35 flood the crank case with oil due to the auxiliary supply which is constant when the engine is in operation, the rise in the level of oil will operate the float 79 to move the valve 90 into position to stop the admission of oil 40 into the chamber of the block 84 through the pipes 81 and 82. When the excess oil has been 45 consumed by engine operation, the float will drop to again allow the oil from the auxiliary storage tanks 26 and 27 to pass into the crank case and directly into the feed pipe 44. With 50 this construction, I provide positive means for maintaining a fixed level of oil in the crank case at all times.

It will be understood that my invention is 55 not limited to the use of two independent auxiliary tanks 26-27, it being apparent that when a single carburetor is employed, one tank disposed at one or both sides of the engine may be employed, and a single admission 60 plug 28 and float level gage 31 employed. Further, it will be apparent that I am not necessarily limited to the specific arrangement of the supply tubes or passages herein shown and described, nor to the bearings or 65 working parts to which they are directed, and

various other changes in and modifications of the construction herein shown and described may be made within the scope of the appended claims without departing from the spirit of my invention or sacrificing its advantages. 70

Having fully described my invention, what I claim as new and desire to secure by Letters-Patent, is:—

1. A lubricating system for internal combustion engines comprising means for transmitting lubricating oil from the crank case of the engine to the working parts under pressure, an auxiliary lubricating oil supply for the crank case, and means for supplying fresh lubricating oil to the crank case and directly to the oil transmitted from the crank case to the working parts. 75

2. A lubricating system for internal combustion engines comprising means for transmitting lubricating oils from the crank case of the engine to the working parts under pressure, an auxiliary lubricating oil supply for the crank case, and means for supplying fresh lubricating oil directly to the oil transmitted 80 from the crank case to the working parts. 85

3. A lubricating system for internal combustion engines comprising means for transmitting oil under pressure from the crank case of the engine to the working parts, a settling and feed chamber into which the oil is first passed prior to its transmission to the working parts, passages in communication with said chamber and directed to the several working parts of the engine, said chamber and passages being exposed to the cooling water of the engine, an auxiliary lubricating oil storage in communication with the crank case, and a valve for controlling and regulating the feed of oil from said auxiliary storage to the crank case, during engine operation. 95 100 105

4. A lubricating system for internal combustion engines employing two carburetors positioned at opposite sides of the engine comprising means for transmitting oil under pressure from the crank case directly to the working parts of the engine, auxiliary lubricating oil storage chambers at the opposite sides of the engine, each of said chambers being in communication with the crank case, and means actuated by the throttle control mechanism of the carburetors for controlling the communication between the separate auxiliary chambers and the crank case. 110 115 120

5. A lubricating system for internal combustion engines employing two carburetors positioned at opposite sides of the engine comprising means for transmitting oil under pressure from the crank case directly to the working parts of the engine, auxiliary lubricating oil storage chambers at the opposite sides of the engine, each of said chambers being in communication with the crank case, and means actuated by the throttle control 125 130 135

mechanism of the carburetors for controlling the communication between the separate auxiliary chambers and the crank case, said last named means being closed when the engine is 5 not in operation.

6. A lubricating system for internal combustion engines employing two carburetors positioned at opposite sides of the engine comprising means for transmitting oil under

10 pressure from the crank case directly to the working parts of the engine, auxiliary lubricating oil storage chambers at the opposite sides of the engine, each of said chambers being in communication with the crank case,

15 means actuated by the throttle control mechanism of the carburetors for controlling the communication between the separate auxiliary chambers and the crank case, said last named means being closed when the engine is

20 not in operation, and said means being adjustable.

7. A lubricating system for internal combustion engines employing two carburetors positioned at opposite sides of the engine

25 comprising means for transmitting oil under pressure from the crank case directly to the working parts of the engine, auxiliary lubricating oil storage chambers at the opposite sides of the engine, each of said cham-

30 bers being in communication with the crank case, means actuated by the throttle control mechanism of the carburetors for controlling the communication between the separate auxiliary chambers and the crank case, said

35 last named means being closed when the engine is not in operation and said means being adjustable, and the transmission of oil from said pressure means being by way of pas-

40 sages exposed to the cooling water of the engine.

8. A lubricating system for internal combustion engines comprising a feed passage arranged horizontally and longitudinally of the engine structure, means for placing said

45 passage in communication with spaced working parts, said passage being exposed to the cooling water of the engine, means for transmitting lubricating oil under pressure from the crank case to said passage, a chamber in-

50 terposed between said means and said passage wherein the oil may settle, an auxiliary lubricating oil storage chamber in communica-

55 tion with the crank case, means for controlling the communication between said storage and said crank case, and means for

55 providing a direct supply of oil from said auxiliary storage to the oil transmitted from the crank case to the feed passage.

9. A lubricating system for sleeve valve in-

60 internal combustion engines employing a main crank shaft and sleeve valve actuating crank shafts, two oil feed passages arranged horizontally and longitudinally of and within

65 the engine structure, one of said passages be-

main crank shaft and the other adjacent the bearings of the second named crank shafts, means for transmitting lubricating oil from the crank case to both of said passages under pressure, means for placing the separate passages in direct communication with the bearings of said crank shafts, and said passages being exposed to the cooling water of the engine.

10. A lubricating system for sleeve valve 75 internal combustion engines employing a main crank shaft and sleeve valve actuating crank shafts, two oil feed passages arranged horizontally and longitudinally of and within

80 the engine structure, one of said passages being in juxtaposition to the bearings of the main crank shaft and the other adjacent the bearings of the second named crank shafts, means for transmitting lubricating oil from the crank case to both of said passages under

85 pressure, means for placing the separate passages in direct communication with the bearings of said crank shafts, said passages being exposed to the cooling water of the engine, and an auxiliary supply of fresh lubri-

90 cating oil to the crank case of the engine.

11. A lubricating system for internal combustion engines comprising means for transmitting oil from a crank case to the working

95 parts of the engine under pressure, means for supplying fresh oil to the oil in the crank case and for maintaining the oil at a predetermined level in the crank case, said last named means including means for introducing oil directly into the first named means.

12. A lubricating system for internal combustion engines comprising means for transmitting oil under pressure from the crank case of the engine to the working parts, a settling and feed chamber integral and within

100 the crank case portion of the cylinder structure and into which the oil is first passed from said crank case prior to its transmission to the working parts through a discharge port at the upper end of said chamber, and a passage opening into the upper end portion of said chamber and in communication

110 with the crank case through said first named means whereby oil may be retained in said chamber below the open end of said passage 115 when the engine operation ceases.

13. A lubricating system for internal combustion engines comprising means for transmitting oil under pressure from the crank case of the engine to the working parts, 120 a settling and feed chamber integral and within the crank case portion of the cylinder structure and into which the oil is first

125 passed from said crank case prior to its transmission to the working parts through a discharge port at the upper end of said chamber, a passage opening into the upper end portion of said chamber and in communication

130 with the crank case through said first named means whereby oil may be retained in

said chamber below the open end of said passage when the engine operation ceases, and a plurality of passages directed to the several working parts of the engine in communication with the discharge port of said chamber.

14. An internal combustion engine, the cylinder structure of which is provided with lubricating passages formed in and as unit parts of the cylinder structure, means extending said passages to the working parts of the engine, said passages being exposed to the cooling water of the engine, a lubricating oil settling and feed chamber formed in the cylinder structure and exposed to the cooling water and with which said passages communicate at the upper end of said chamber, and means involving a passage opening into the upper end portion of said chamber through which oil is passed for admission into said chamber for retaining oil in said chamber when the engine ceases operation.

15. An internal combustion engine, the cylinder structure of which is provided with lubricating passages formed in and as unit parts of the cylinder structure, means extending said passages to the working parts of the engine, said passages being exposed to the cooling water of the engine, a lubricating oil settling and feed chamber formed in the cylinder structure and exposed to the cooling water and with which said passages communicate at the upper end of said chamber, means involving a passage opening into the upper end portion of said chamber through which oil is passed for admission into said chamber for retaining oil in said chamber when the engine ceases operation, an auxiliary lubricating oil storage in communication with the crank case, and a valve for controlling and regulating the feed of oil from said auxiliary storage to the crank case, the communication between said auxiliary storage being closed when the engine is not in operation.

16. An internal combustion engine, the cylinder structure of which is provided with lubricating passages formed in and as unit parts of the cylinder structure, means extending said passages to the working parts of the engine, said passages being exposed to the cooling water of the engine, a lubricating oil settling and feed chamber formed in the cylinder structure and exposed to the cooling water and with which said passages communicate at the upper end of said chamber, means involving a passage opening into the upper end portion of said chamber through which oil is passed for admission into said chamber for retaining oil in said chamber when the engine ceases operation, an auxiliary lubricating oil storage in communication with the crank case, and a valve for controlling and regulating the feed of oil from said auxiliary storage to the crank case, the communication between said auxiliary storage being closed when the engine is not in operation.

17. An internal combustion engine, the cylinder structure of which is provided with lubricating passages formed in and as unit parts of the cylinder structure, means ex-

age being closed when the engine is not in operation, and means for directing oil from the auxiliary storage into the oil transmitted directly to the working parts from the oil in the crank case.

18. An internal combustion engine, the cylinder structure of which is provided with lubricating passages formed in and as unit parts of the cylinder structure, means extending said passages to the working parts of the engine, said passages being exposed to the cooling water of the engine, a lubricating oil settling and feed chamber formed in the cylinder structure and exposed to the cooling water and with which said passages communicate at the upper end of said chamber, means involving a passage opening into the upper end portion of said chamber through which oil is passed for admission into said chamber for retaining oil in said chamber when the engine ceases operation, an auxiliary lubricating oil storage in communication with the crank case, and a valve for controlling and regulating the feed of oil from said auxiliary storage to the crank case, the communication between said auxiliary storage being closed when the engine is not in operation, means for directing oil from the auxiliary storage into the oil transmitted directly to the working parts from the oil in the crank case, and a strainer arranged horizontally within the crank case and covering the major portion of the area thereof.

19. An internal combustion engine, the cylinder structure of which is provided with lubricating passages formed in and as unit parts of the cylinder structure, means extending said passages to the working parts of the engine, said passages being exposed to the cooling water of the engine, a lubricating oil settling and feed chamber formed in the cylinder structure and exposed to the cooling water and with which said passages communicate at the upper end of said chamber, means involving a passage opening into the upper end portion of said chamber through which oil is passed for admission into said chamber for retaining oil in said chamber when the engine ceases operation, an auxiliary lubricating oil storage in communication with the crank case and a valve for controlling and regulating the feed of oil from said auxiliary storage to the crank case, the communication between said auxiliary storage being closed when the engine is not in operation, means for directing oil from the auxiliary storage into the oil transmitted directly to the working parts from the oil in the crank case, a strainer arranged horizontally within the crank case and covering the major portion of the area thereof, and another strainer within the crank case below the first named strainer and through which oil directed to the working parts is passed.

20. A lubricating system for internal com-

bustion engines comprising means for transmitting lubricating oil from the crank case of the engine to the working parts under pressure, an auxiliary lubricating oil supply for the crank case, and means actuated by the fuel feed controlling means of the engine when in operation for supplying fresh lubri-

cating oil from said auxiliary supply to the crank case.

In testimony that I claim the foregoing as my invention I have signed my name this 23rd day of Sept., 1925.

FRANK E. LONAS.
